DRAWER PULL

Harold H. Ring, Rockford, Ill., assignor to Amerock
Corporation, a corporation of Illinois

Application October 27, 1955, Serial No. 38,600

Term of patent 14 years

(Cl. D10—8)

Fig. 1

Fig. 2

Fig. 3

Figure 1 is a front elevation of a drawer pull, showing my new design.

Fig. 2 is a plan view.

Fig. 3 is an end view.

Fig. 4 is a sectional view taken along the line 4—4 in Fig. 1.

Fig. 5 is a sectional view taken along the line 5—5 in Fig. 1.

I claim:

The ornamental design for a drawer pull, substantially as shown.
